UNITED STATES PATENT OFFICE.

EDWARD A. BRIGGS, OF HOPEWELL, NEW JERSEY, ASSIGNOR OF ONE-HALF TO FRANCIS PETTIT, OF HOPEWELL, NEW JERSEY.

DUAL IGNITION SYSTEM FOR INTERNAL-COMBUSTION MOTORS.

1,165,492.

Specification of Letters Patent.

Patented Dec. 28, 1915.

Application filed April 14, 1915. Serial No. 21,241.

To all whom it may concern:

Be it known that I, EDWARD A. BRIGGS, a citizen of the United States, residing at Hopewell, in the county of Mercer and State 5 of New Jersey, have invented certain new and useful Improvements in Dual Ignition Systems for Internal-Combustion Motors, of which the following is a specification, reference being had therein to the accompanying 10 drawing.

This invention has relation to dual ignition systems for internal combustion motors, and particularly for motors on automobiles of the Ford type, and has for its object the 15 provision of novel means for the application and utilization, for ignition purposes, of high tension magnetos in running the car in connection with the usual low tension magneto and battery, with which Ford cars 20 are now equipped, to be used for starting and lighting purposes.

It is well known and understood that while a high tension current system is the best on which to run a car, it is very unsatisfactory when starting, and it is also well known that the low tension current system, such as now used on Ford cars, is imperfect during the running of the car for the reason that it does not give perfect 30 synchronism of firing at the cylinders.

My present invention aims at combining in one motor equipment the advantageous features of both high and low tension systems, with means for properly switching 35 them in and out of alternate use, so that the low tension system may be used when starting and the high tension system used in running, and so that during the running of the car on the high tension current, the low tension 40 current may be used for lighting purposes.

A further object of the invention is to enable the car to be run, in emergencies, on either the low tension magneto alone, the 45 batteries alone, the high tension magneto alone, or on any combination of the three systems, and for the purpose of enabling the several systems to be so used with efficacy and convenience, I provide means for advancing or regulating in synchronism, the 50 time of ignition by both the high and low tension systems.

My invention consists in the novel construction, combination and arrangement of

parts hereinafter described and claimed, 55 reference being had to the accompanying drawings, in which:

Figure 1 is a diagram showing the relation of the several ignition systems to the engine, and the course of the currents. Fig. 60 2 is a front elevation of part of a Ford car equipped with the supporting means, for a high tension magneto and gearing train for operating the same. Fig. 3 is a side view of the parts illustrated in Fig. 2. Fig. 4 is a 65 vertical sectional view of one of the double terminal spark plugs which I employ.

Assuming that the devices embodying my invention are shown as applied to a Ford car, 1, in the drawing designates a casting, 70 which is substituted in the place of the present casting or front plate of the Ford engine, and which is bolted to the bed plate.

The plate or casting 1, which is the support or bearing for the commutator or timer 75 10, extends laterally some distance beyond the position occupied by the ordinary front plate, and is formed with a rearward horizontal extension 2, at one end, and at the lower edge, for the accommodation of a platform 3, to support a high tension magneto 4. This platform is vertically adjustable to adapt it for the reception of magnetos of different heights and types and for this purpose is provided with depending standards 80 85 or legs 5, which slide in socketed blocks 6, formed on the underside of the extension 2. An adjusting screw 7, provided with a flat head 8, on its upper end and an operating handle 9, on its lower end, has its bearing 90 in the metal of the extension 2, and is used for the adjustment of the platform 3, to different heights.

The timer or commutator 10, is mounted on a shaft 11, which receives motion from the 95 main power shaft, and on the same shaft 11, is keyed or fastened a large toothed wheel 12, which engages with an idler 13, of smaller size, which in turn is in mesh with a pinion 14, the shaft 15 of which communicates motion to the armature of the high tension magneto 4, the speed of the latter being, therefore, increased above that of the timer shaft. The timer or commutator 16, of the high tension magneto, and the commutator 10, of the low tension magneto, are both 100 105 coupled by separate connecting rods 17 and 18, to the timing rod 19, of the steering shaft.

of the car, so that both commutators or timers may be adjusted to advance or retard the spark ignition periods synchronously.

The plate 1, is formed with a gear casing 21, on its face, which is covered by a protecting plate 22, bolted to the flanges of the casing 21, and the several gear wheels 12, 13, 14, lie within this casing, the plate 1 forming a bearing for the shafts 10', 15, of the wheels 13 and 14.

Nuts 23 and 24 are fitted to the outer ends of the shafts 10', 15, and project into bosses 10², 11², formed on the protecting cover plate 22. As the shaft 15, of the pinion 14, is extended rearwardly and coupled to the armature shaft 12², of the high tension magneto in alignment therewith, through coupling plates, the plate 1 is formed with a rearwardly projecting bearing boss or box 25, which is preferably provided with a bronze bushing 26.

Each cylinder of the engine is provided with a double terminal spark plug 29, one of said plugs being shown in sectional view in Fig. 4, and the two sparking terminals, one for the high tension magneto and the other for the coil system, are designated respectively 29', 29'', connection being effected with the sparking terminals by means of suitable binding screws as shown.

The electrical connections are shown in the diagram Fig. 1, in which is represented four coil units 27, four engines 28, with their spark plugs 29, a switch 30, and the battery 31, low tension magneto 32, and high tension magneto 33. The switch 30, which is to be mounted on the dash board, or other convenient part of the car, comprises a base board 35, a switch lever 36, and contacts 37', 37, 38, 39, 40, 41, the first named being the pivoted bearing of the lever and is in circuit with the primary leading to the spark coils and thence through the timer to ground. Contact 37, leads to one pole of the battery 31, the other pole of which leads to ground. Contact 38, leads to the low tension magneto 32, thence to ground. Contact 39, is simply neutral, and when the switch lever is thereon, the low tension magneto and battery are cut out. Under such last named conditions, the high tension magneto is in circuit through its timer with one terminal of each of the spark plugs of the engines, and thence to ground. The circuit of the low tension magneto is by a line 46, from the low tension magneto to contact 38, thence by switch lever 36, to contact 36', thence by a line 47, to a point 48, where the four ends of the primary wires of the four coils 27, meet, thence by four wires 43, to the timer 10, and through the shaft of the timer to ground by line 50, and from ground to the low tension magneto by the line 51. The battery circuit, starting at ground, is by line 52, to battery 31, thence by line 53, to contact 37, through

switch lever 36 to contact 30, thence by line 47, to point 48, where the ends of the four primary wires of the four coils 27, meet, thence by lines 43, to timer 10, and thence by line 50 to ground. The circuits of the secondary wires of the four coils 27, one end of each of which is grounded, are through the four lines 54 to one terminal of each of the spark plugs 29, and thence through cylinders 28, to ground by lines 55, while the circuits to the spark plugs of the high tension magneto 33, are through the four lines 56, to the spark plugs 29, and through the cylinders 28, to ground. A short circuit for the high tension magneto is provided by way of a line 42 to contact 40, by switch lever 36, (when it is resting on contact 40) to a spring tongue 49, thence to contact 41, and thence to ground by line 44.

The parts being constructed and arranged as above described, operate in the following manner: Before starting the engine the switch lever 36, is turned so as to rest on contact 38. This places the low tension magneto 33, in circuit with the primary wires of coils 27, and with timer 10, and the current from the secondary windings of coils 27, will be delivered in succession to the spark plugs 29 of cylinders 28. At the same time, the circuit of the high tension magneto 32, will be closed and as the timer of the latter through the movement imparted to it by train of gearing 12, 13, 14, will be rotated, current will be delivered from the high tension magneto to the spark plugs simultaneously with the delivery thereto of the current from the low tension magneto. When the car has been started, the switch lever can then be turned to contact 39, which will throw the low tension magneto out of circuit with the coils 27, but leave the high tension magneto in circuit to alone supply current to the spark plugs. If desired, the ignition may be effected by the battery and the high tension magneto by moving the switch lever 36, so as to rest on contact 37, the high tension magneto being at this position of the lever in circuit with and also supplying current to the spark plugs. While current is being supplied to the spark plugs by the battery and the high tension magneto, or by the high tension magneto alone, the current from the low tension magneto may be utilized for lighting purposes. When it is desired to stop all supply of current to the spark plugs it is only necessary to move the switch lever 36 over until it rests on contact 40 at which position it will also touch the spring contact 49, and thus short circuit the high tension magneto and render it inoperative for the supply of current to the spark plugs.

I claim:—

1. In a dual ignition system for internal combustion motors, the combination with a car and an engine and its main shaft, a low

- tension magneto mounted on said main shaft and a timer receiving motion from said shaft, of a plate or casting extending laterally from the said main shaft and having a 5 rearward extension, a vertically adjustable platform mounted on said extension, a high tension magneto mounted on said platform and carrying a timer, a train of gearing communicating motion from the shaft of the 10 timer of the low tension magneto to the armature and timer of the high tension magneto, a timing rod carried by the steering shaft of the car and separate rods connecting said timing rod to the timers of the low 15 tension magneto and the high tension magneto.
2. In a dual ignition system for internal combustion motors, the combination with a car and an engine and its main shaft, a low 20 tension magneto mounted on said main shaft and a timer receiving motion from said shaft, of a plate or casting extending laterally from the said main shaft and having a rearward extension, a high tension magneto mounted 25 on said extension and carrying a timer, a train of gearing communicating motion from the shaft of the timer of the low tension
- magneto to the armature and timer of the high tension magneto, a timing rod carried by the steering shaft of the car and separate 30 rods connecting said timing rod to the timers of the low tension magneto and the high tension magneto.
3. In a dual ignition system for internal combustion motor cars, the combination with a low tension magneto and its timer adapted 35 to receive motion from the main shaft of the motor of the car and a high tension magneto and its timer geared to the timer of the low tension motor, and a battery, of means for 40 simultaneously adjusting the timers of both said magnetos and a switch adapted to successively electrically connect the battery and high tension magneto simultaneously to the spark plugs of the engine, and the low tension magneto and the high tension magneto simultaneously to the spark plugs of the engine. 45

In testimony whereof I affix my signature in presence of two witnesses.

EDWARD A. BRIGGS.
